UNITED STATES PATENT OFFICE.

ALBERT LEICHT, OF SHEBOYGAN, WISCONSIN.

PENCIL-SHARPENER.

1,131,529.

Specification of Letters Patent.

Patented Mar. 9, 1915.

Application filed October 9, 1911. Serial No. 653,659.

To all whom it may concern:

Be it known that I, ALBERT LEICHT, a citizen of the United States, residing at Sheboygan, in the county of Sheboygan and State 5 of Wisconsin, have invented certain new and useful Improvements in Pencil-Sharpener; and I do hereby declare the following to be a full, clear, and exact description of the invention, such as will enable others skilled 10 in the art to which it appertains to make and use the same.

This invention relates to pencil sharpeners and has for its object to provide a device of this nature, known commonly as the rotary 15 pencil sharpener, wherein a smooth and conical point is produced and the pressure of the pencil upon the sharpening wheel may be automatically regulated.

A further object of this invention is to 20 provide a means whereby the sharpening material carried by the wheel or drum may be removed and a new element substituted therefor.

Among the other objects of this invention 25 is the provision of a means whereby the dust and dirt produced in the process of sharpening may be accumulated entirely within the body of the machine.

With the above and other objects in view, 30 this invention consists in the construction, combination and arrangement of parts, as hereinafter more particularly described, claimed and illustrated, in which—

Figure 1 is a central, vertical section of a 35 pencil sharpener, constructed in accordance with the present invention; Fig. 2 is a side elevation, parts thereof being in section, of the pencil retaining clamp; Fig. 3 is a fragmentary section elevation, illustrating means 40 whereby the sharpening element is secured to the drum and adapted to carry the same; Fig. 4 is a fragmentary view of said sharpening element.

Reference being had more particularly to 45 the drawings, 10 indicates a base of any suitable construction, having secured thereto the casing 11, said casing being mainly circular, in order to provide for the free rotation of the sharpening drum therein. A 50 bearing or bracket 12 is secured to one side of the casing 11, and has mounted therein a shaft 13, which protrudes into the casing 11 and rests normally flush with the opposite face thereof. A sleeve 14 is mounted for 55 rotation upon the shafts 13, and is provided adjacent to the bracket 12 with an enlarge-

ment 15, said enlargement operating between the bracket 12 and the adjoining face of the casing 11, and is provided with a V-shaped groove 16 adapted to receive the belt, as will 60 hereinafter be more fully described. An arm 17 projects from the sleeve 14 and carries at the outer terminal thereof, a spring drum 18, the adjoining terminals of which are adapted to be forced together by the resiliency of the material of which the drum 18 is constructed, as illustrated in Fig. 3, as will be hereinafter more fully described. The opposite face of the casing 11 and the bracket 12 is provided with a semi-circular 70 opening 19 somewhat larger in diameter than the diameter of the spring drum 18, in which is mounted for rotation a face plate 20, said face plate being threaded into engagement with the sleeve 14 and provided 75 with a handle 21 in such a manner that as the force is applied to the handle 21, a rotary motion will be imparted to the face plate 20, and consequently the sleeve 14 and the drum 18.

The abutting terminals 18^a and 18^b of the spring drum 18, as has heretofore been stated, are forced together by the resiliency and spring of the material of which said drum is constructed, and this construction 80 permits the strip of sand paper or other suitable material 22 to be placed upon a spring drum when the same is contracted to be retained thereon after the terminals 85 thereof have been moved in divergent directions. When it is desired to remove this strip of material from the drum 18, an inwardly extending projection 23 is formed upon the inner surface of the terminal 18^a, and coöperates with the eccentric 24, which 90 is pivotally mounted on the under surface of the terminal 18^a. It will be seen that when it is desired to remove the sandpaper from the drum the face plate 20 is removed and the eccentric 24 forced outwardly, 95 thereby causing it to exert a pressure upon the projection 23, moving the terminals 18^a and 18^b in opposite directions, thus permitting the sand paper to readily be removed. A blank strip of material 25 is secured to 100 the under side of the sand paper 22 in any suitable position, in such a manner that the projecting terminal thereof may be engaged and the sand paper removed without soiling the hands of the operator. This strip 105 110 is a piece of ordinary blank paper attached diagonally across the under side of the

abradant surface having one corner projecting beyond the abradant rim to afford a means for grasping said rim when it is to be replaced without necessitating the operator's coming in contact with the soiled rim. The upper terminal of the casing is provided with a depression 26, which adjoins the opening 27, and into which the pencil is adapted to be projected. A bearing 28 is mounted on the casing 11 directly above the bracket or bearing 12, and has mounted therein through the medium of a horizontal pivot a pencil clamp indicated generally as "A." The bearing 28 is provided with a vertical adjustment through means of the slot and securing connections 29 and 30.

The specific structure of the pencil clamp is as follows: The bearing 31 is mounted in the bracket 28 through the instrumentality of the diametrical lugs 32, which are pivoted in the arms of the bracket, and which provide a means whereby the bearing 31 may operate about a horizontal pivot. A pulley 33 is mounted in the bearing 31 through the instrumentality of the depression 34, and is adapted to receive the bearing and rotatably retain the pulley within said bearing. The body portion of the pulley is connected by a coil spring belt 35, with the depression 16 and the projection 15 formed on the sleeve 14. Thus, upon the rotation of said sleeve, said pulley will rotate within the bearing 31. A follower 36 mounted in the outer terminal of the pulley 33 is adapted to project therefrom by a spring 37 illustrated in Fig. 3, mounted within the pulley 33 under the depression 34. This follower carries a plurality of spring arms 38, which at their inner terminals are provided with the pencil engaging clamps 39, which engage the pencil "P" and firmly retain the same within the pulley. These pencil engaging clamps are rotated substantially within the pulley 33, and are provided with the notches 40 which engage the depression

41 formed on the inner surface of the pulley, thus retaining the follower in engagement with said pulley.

From the foregoing it will readily be seen that when the pencil "P" is inserted into the follower 36 and in the pulley 33, the same will be engaged by the pencil engaging clamps 39, due to the spring arms 38, which converge said pencil engaging clamps inwardly, by reason of the fact that the bearing 31 is pivoted in the bracket 28 and permits the coil spring belt 35 to draw the pencil into engagement with the sand paper sheet 22 carried by the spring drum 18, as illustrated in Fig. 1. Therefore, upon the rotation of the spring drum 18 and consequently the sleeve 14, the pencil will likewise be rotated, causing the thorough and positive sharpening thereof.

A suitable drawer 42 is mounted adjacent to the base 10 under the drum 18 and is adapted to receive all dust created by the pencil sharpening operation.

Having thus fully described my invention, what I claim as new, and desire to secure by U. S. Letters Patent, is—

In a pencil sharpener, the combination with a split spring drum, of a sharpening surface mounted upon said drum and adapted to be secured between the terminals thereof by means of the spring embodied in said drum, a plate secured to one terminal of said drum upon the inner surface thereof at a point centrally of the sides of said drum, and a cam lever pivotally secured to the other terminal of said drum at a point centrally of the sides thereof adapted to engage said plate, whereby the terminals of said drum may be forced apart to release said sharpening surface.

In testimony whereof I affix my signature in presence of two witnesses.

ALBERT LEICHT.
